W. E. NICKERSON,
BLADE STROPPING DEVICE,
APPLICATION FILED OCT. 25, 1917.

1,283,872.

Patented Nov. 5, 1918.

W. E. NICKERSON,
By E. D. Chadwick,
His ATTORNEY.

UNITED STATES PATENT OFFICE.

WILLIAM E. NICKERSON, OF CAMBRIDGE, MASSACHUSETTS, ASSIGNOR TO GILLETTE SAFETY RAZOR COMPANY, OF BOSTON, MASSACHUSETTS, A CORPORATION OF DELAWARE.

BLADE-STROPPING DEVICE.

1,283,872.

Specification of Letters Patent.

Patented Nov. 5, 1918.

Original application filed January 26, 1916. Serial No. 74,394. Divided and this application filed October 25, 1917. Serial No. 198,520.

To all whom it may concern:

Be it known that I, WILLIAM E. NICKERSON, a citizen of the United States, residing at Cambridge, in the county of Middlesex 5 and State of Massachusetts, have invented certain new and useful Improvements in Blade-Stropping Devices, of which the following is a specification.

My invention relates to sharpening devices 10 in which the abrasive surface is provided by a detachable strip of leather or other flexible material, and has for its object the provision of simple and effective means whereby the flexible strip may be readily attached to or 15 detached from the part which carries it and maintained under tension while in use. The particular embodiment of my invention herein described is a rotary stropping device which is designed for use in a blade-stropping 20 machine of the character set forth in my co-pending application, Serial No. 74,394, filed January 26, 1916, of which the present application is a division.

In the accompanying drawings illustrating my invention:

Figure 1 is an end view of the blade-stropping device above referred to as preferably constructed.

Fig. 2 shows the device in transverse section; and

Fig. 3 is a longitudinal section on the line $x-x$ in Fig. 1.

In the rotary stropping device illustrated the body portion which serves as the carrier 35 for the flexible strip consists of a frame 2 having substantially the form of a segment of a cylinder and including a central hub 3 which is bored longitudinally for the reception of the shaft 4 by which the device is 40 rotated and to which it is removably secured by means of a clamping nut 5 on the threaded extremity of the shaft. A notched collar 6 splined to the shaft 4 between the nut 5 and the hub 3 interlocks with the similarly- 45 notched end of the hub and prevents relative rotation of the shaft and hub. The curved outer surface of the frame 2, which is concentric with the axis of the shaft, extends circumferentially through about one-half of 50 the complete circumference of a cylinder of corresponding diameter and carries the flexible strip 7, made of leather, which passes around and is supported by said curved outer surface and has its ends secured to the

frame at points which lie between the central axis of the latter and the cylindrical path in which the outer face of the strip moves when the device is rotated. A pad 8 of felt or similar material is preferably interposed between the frame and the strip 7, 60 in order to provide a sufficiently yielding stropping surface.

For securing the ends of the strip 7 to the frame 2 I employ a rod 9 extending lengthwise of the frame and carried by pivot bolts 10 passing through end flanges 11 on the hub 3 and screwed into the opposite ends of the rod, which is provided with two longitudinally-extending series of substantially radial pins 12. The ends of the strip 7 overlap the rod 9 on opposite sides of the latter and are provided with perforations which receive the corresponding series of pins 12, and after the strip has thus been connected to the rod one end of a suitable lever is inserted into a recess 13 formed in one side of said rod and the latter is rotated until the strip is subjected to the desired tension, whereupon the rod is immovably clamped by tightening the pivot bolts 10. By means of the arrangement just described the strip can be readily attached to and detached from the frame and firmly held under any desired tension, and since the tension is applied equally and simultaneously to both ends of the strip the latter is subjected to a substantially uniform tension throughout and has no tendency to slip longitudinally.

The particular form of stropping device above described is intended for use in a machine in which two such devices are arranged to operate alternately on the same blade, which is the reason for limiting the stropping surface to a little less than half a complete circumference, but it will be evident 90 that the same strip-attaching means may be employed in similar stropping devices which operate through more than half a circumference, if desired. It will also be evident that the invention may be embodied in other 95 forms of stropping devices, and in various other devices containing a flexible strip held under tension.

I claim:

1. A device of the character described, 105 comprising a frame having the form of a segment of a cylinder and including end flanges located within the periphery of the

- cylinder and providing an open space between them, an exposed rod pivotally mounted in the end flanges, diametrically opposite the center of the segment, a flexible strip 5 passing around the cylindrical portion of the frame, means carried by the rod for engaging the exposed ends of the strip simultaneously, and means for clamping the rod in fixed relation to the frame and strip.
- 10 2. A device of the character described, comprising a frame having the form of a segment of a cylinder and including a central hub adapted to be mounted on a shaft

and end flanges located within the periphery of the cylinder, a rod pivotally mounted in 15 the end flanges and provided on opposite sides with lines of outwardly-extending pins, a flexible strip passing around the cylindrical portion of the frame and having its ends perforated to receive said lines of pins 20 respectively, and means for clamping the rod in fixed relation to the frame and strip.

Signed at Boston, Mass., this 19th day of October, 1917.

WILLIAM E. NICKERSON.
